UNITED STATES PATENT OFFICE

123,755

DESIGN FOR A COMBINED CIGARETTE HOLDER AND ASH TRAY

Joseph Mortimer Lichtenauer, Westport, Conn.

Application August 8, 1940, Serial No. 94,302

Term of patent 7 years

To all whom it may concern:

Be it known that I, Joseph Mortimer Lichtenauer, a citizen of the United States and resident of Westport, in the county of Fairfield and State of Connecticut, have invented a new, original, and ornamental Design for a Combined Cigarette Holder and Ash Tray, of which the following is a specification, reference being had to the accompanying drawing, forming a part thereof.

Fig. 1 represents a side elevation of a combined cigarette holder and ash tray showing my new design;

Fig. 2 represents a plan view of the same; and
Fig. 3 represents an end elevational view, as

I claim:

The ornamental design for a combined cigarette holder and ash tray, as shown.

JOSEPH MORTIMER LICHTENAUER.
